UNITED STATES PATENT OFFICE.

HERMAN C. MUELLER, OF MILWAUKEE, WISCONSIN.

INTERNAL-COMBUSTION ENGINE.

Specification of Letters Patent. Patented Mar. 29, 1921.

1,372,896.

Application filed December 24, 1917. Serial No. 208,703.

To all whom it may concern:

Be it known that I, HERMAN C. MUELLER, a citizen of the United States, residing at Milwaukee, county of Milwaukee, and State of Wisconsin, have invented new and useful Improvements in Internal-Combustion Engines, of which the following is a specification.

My invention relates to improvements in internal combustion engines of that type in which an auxiliary chamber is provided to receive fuel from a source of supply, and air from the cylinder, preparatory to and during the compression stroke of the engine piston, the heat of compression being added to that radiating inwardly from the walls of the chamber, to vaporize and then ignite the mixture preparatory to its delivery to the cylinder as a slow burning mixture capable of rapid distribution and combination with the cylinder air as soon as the pressure in the auxiliary chamber exceeds that developed by the piston in the cylinder itself.

Engines of this type, including two cycle engines, develop high efficiency and are capable of utilizing fuels of high specific gravity and low volatility, the temperature in the auxiliary chamber being sufficiently high to vaporize such fuels in part before ignition and in some instances after initial combustion of the more volatile portions has raised the temperature above that developed by compression. But heretofore considerable difficulty has been experienced in keeping the fuel inlet free from carbon, particularly where valves are employed to control the fuel delivery. It has also been found in practice that where an ordinary valve is employed, slight particles of sediment, or of carbon, prevent the valve from seating properly, and during the compression stroke, quantities of the combustible mixture are driven into the air and fuel passages, thereby not only destroying the efficiency of the engine by preventing a proper mixture from being delivered, but quickly clogging the passages with deposits of carbon and making it necessary to stop the engine and clean the passages or replace the elements through which they pass.

The object of my invention is to overcome the above difficulties by providing a ported rotary valve which will wear to its seat, but in which the wear will be reduced to a minimum by operating the valve during the exhaust period, or during the beginning of the

compression stroke, the valve being then under light pressure and easily rotated. A further object of my invention is to provide an improved form of valve whereby the pressure exerted by the fuel and air may be substantially balanced, and whereby effective mixing and distribution of the mixture throughout the auxiliary chamber may be secured.

In the drawings:

Figure 1 is a sectional view of an internal combustion engine, drawn generally to a plane common to the axes of the fuel inlet and air ducts leading to the auxiliary combustion chamber.

Fig. 2 is a cross section of the auxiliary chamber, showing the inlet controlling valve in full.

Fig. 3 is a detail view of the ported inlet plug, with the valve removed.

Fig. 4 is an enlarged detail view of the valve.

Like parts are identified by the same reference characters throughout the several views.

The cylinder 1, piston 2, exhaust passage 3, exhaust valve 4, and fuel-inlet passage 5 may be of any ordinary construction, and therefore need not be more fully described.

The cylinder head 7 is provided with an opening leading to the fuel inlet duct 5, in which a cup shaped member 8 is seated, this member providing the inner walls of the auxiliary chamber, and having one or more outlet ports 9 communicating with the cylinder through the passage 5. A plug 10, fitted to the opening in the cylinder head and to the rear portions of the cup shaped member 8, is provided with an air passage 11 along its axis, and this air passage is enlarged at its inner end to form a conically tapered valve seat at 12, adapted to receive a valve 13 having a correspondingly tapered seating face, and provided with an operating stem 100 14. The seating face of the valve is provided with a groove 15 leading from the passage 11, and the valve is provided with a passage 17 leading from its seating face through the valve, and adapted to permit air delivery from the passage 11 through the groove 15 and passage 17 into the auxiliary chamber, when the passage 17 is in registry with the groove 15.

The member 10 is also provided with a fuel passage 20, with which a fuel inlet duct 21 communicates. This passage is reduced

at its lower end and also leads through the seating face of the valve at 22. The valve is provided with a passage 23 leading through its seating face to the passage 17, 5 and also communicating with the auxiliary chamber through an independent passage or port 25. The passage 23 is adapted for registry with the fuel inlet duct simultaneously with the registry of passage 17 10 with the groove 23, whereby air and fuel may be simultaneously admitted to the auxiliary chamber through the ducts 11 and 20 respectively.

The upper end of the air passage 11 is 15 closed by a plug 27, through which the valve stem 14 passes, and through which air is admitted to the duct 11 from the exterior through a cross passage 28, having a ported plug 29, to control or limit the quantity of 20 air admitted.

With the above described construction, it is obvious that the air and fuel inlets for the auxiliary chamber may be simultaneously closed by rotating the valve 13 upon 25 its seat to carry the ducts 17 and 23 out of registry with the groove 15 and port 22. In operation, the valve 13 will be rotated to the Fig. 1 position to admit fuel and air to the auxiliary chamber or cavity formed between the valve and opposing surfaces of 30 the member 8. In a four cycle engine this may occur during the suction stroke of the piston. In a two cycle engine the valve will be so adjusted to admit fuel and air while 35 the piston is at, or near, the limit of its outward stroke, and air and fuel may then be injected into the auxiliary chamber from any suitable source of supply, and under any desired pressure, sufficient to provide the 40 requisite quantity of each. The injection of the fuel into the auxiliary chamber may take place during the initial portion of the compression stroke, but in any case the valve 13 will be rotated to close the air and 45 fuel inlet ducts before the pressure has been raised to a point where the operation of the valve will require any considerable force, thus avoiding excessive wear of the valve upon its seat.

50 During the final portion of the compression stroke the pressure within the auxiliary chamber will be sufficient to ignite the fuel therein, the construction being such that the piston moves into close proximity to the cylinder head, the space in the passage 5 and within the auxiliary chamber being small, 55 whereby a high pressure may be developed. The passages 17 and 23, and also the port 25, are too small to allow combustion to take 60 place within them, the mixture of fuel within the auxiliary chamber being of such a character that only slow combustion is permitted for a brief interval, pending the discharge of the fluid into the cylinder as 65 soon as the pressure in the auxiliary chamber

ber has been raised to a point above that in the cylinder. Any tendency of the passages 17 and 23 and of the port 25 to become clogged is counteracted by the forcible delivery of air and fuel through these passages, the kinetic energy developed within the passages tending to carry away all material which tends to precipitate upon the walls thereof. 70

It will be observed that the valve stem 14 75 is provided with an operating lever 30, whereby it may be oscillated into and out of open position, motion being derived from a cam shaft (not shown) in an ordinary manner, it not being deemed necessary to show 80 the connections. It is well understood that in this manner the movements of the valve may be properly timed. The needle valve 32 is also connected by its stem 33 with an operating lever, the latter being actuated 85 either manually or from a governor, as may be desired.

It will also be observed that the valve 13 is resiliently held to its seat by a spring 35 interposed between the outer end of the plug 90 10 and a collar 36, threaded on the valve stem 14. This is desirable in order that the valve may be held continuously upon the seat, thereby preventing sediment from becoming interposed between the valve and its 95 seat, as is the case where valves are employed which move to and from their seats, as has heretofore been the practice with this type of engines.

I claim:

1. An internal combustion engine, including the combination with the cylinder, of an auxiliary chamber provided with air and fuel admission ducts, and ported for communication with the cylinder, a valve 105 controlling air and fuel delivery through the inlet ducts to the auxiliary chamber, said valve having passages therethrough, adapted in one position of rotative adjustment to register with said ducts, and means 110 for intermittently rotating said valve upon its seat, during the intervals of low pressure within the cylinder.

2. In an internal combustion engine, having an auxiliary fuel vaporizing and mixing chamber organized to utilize the heat of compression to ignite a slow burning mixture in the auxiliary chamber, the combination with an auxiliary chamber wall provided with a conically tapered valve seat, 115 air and fuel inlet passages leading therethrough below the apex, of a conically tapered valve provided with an air passage leading therethrough, and adapted for registry with the air passage in the valve 120 seat, said valve also having a passage adapted for simultaneous registry with the fuel inlet passage in the valve seat, and means for periodically oscillating the valve about an axis intersecting the apex and the center 125 130

of its base to open and close said inlet passages.

3. The combination with the cylinder, of an internal combustion engine, having an auxiliary chamber provided with air and fuel admission ducts, of a rotative valve controlling air and fuel deliveries to the auxiliary chamber through said ducts, said auxiliary chamber being adapted to discharge its contents into the cylinder, and means for periodically oscillating the valve about an axis through its apex and the center of its base to open and close said ducts.

4. In a high pressure self-igniting internal combustion engine having a cylinder provided with an auxiliary ignition chamber in communication with the cylinder, and also provided with a fuel inlet duct, a rotary valve controlling fuel deliveries through said duct, and means for admitting sufficient air to said auxiliary chamber to allow a slow combustion of said fuel within the chamber.

5. An internal combustion engine, of the high pressure self-igniting type, including the combination with the engine cylinder, of an auxiliary chamber having separate air and fuel inlet ducts, and a rotatively adjustable valve, controlling deliveries through both of said ducts, said valve having passages therethrough adapted in one position of valve adjustment to connect said air and fuel inlet ducts with the interior of said

chamber, and in another position to separately close both ducts, said auxiliary chamber having a constantly open outlet port leading to the cylinder. 35

6. An internal combustion engine, including the combination with the cylinder, of an auxiliary chamber, having a conical valve seat provided with fuel and air inlet ports, in the sloping surfaces of the seat, a conical valve controlling deliveries through both of said ports, said valve having passages therethrough, and adapted when oscillated rotatively upon the seat to connect and disconnect the ports with said auxiliary chamber, and a valve stem provided with an oscillatory valve actuating member. 40 45

7. The combination with a cylinder of an internal combustion engine having an auxiliary chamber provided with air and fuel admission ducts, of a valve seat, ported for communication between said ducts and the auxiliary chamber, a valve adapted for sliding movement upon the seat, to open and close said ports while remaining in contact with the seat, and an oscillatory valve actuating member. 50 55

In testimony whereof I affix my signature in the presence of two witnesses.
